BURNER MOUNTING IN AIR HEATERS

Hugh M. Blumenshine, Whittier, Calif., assignor to Holly Division, Lear Siegler, Inc., South Gate, Calif., a corporation of Delaware

Filed May 10, 1965, Ser. No. 454,445

3 Claims. (Cl. 158—7)

This invention relates to air heaters and, more particularly, to means for releasably mounting a gas-fired burner assembly to a tubular heat exchanger of an air heater adjacent an open lower end of the heat exchanger.

Gas-fired air heaters of the type which are mountable vertically either to the exterior or the interior of a wall in a dwelling, for example, commonly include a vertically disposed tubular heat exchanger, and a thermostatically controlled burner assembly mounted adjacent the open lower end of the heat exchanger. In order that the air heaters may be installed between the studs in a wall, which studs normally have a spacing of 18 inches, the air heater must be compact in construction. Existing air heaters have the burner assembly removably secured to the heat exchanger by nuts and bolts to facilitate removal of the burner assembly for servicing and the like. Because of the necessary compactness of construction, however, these nuts and bolts often must be placed in such a position that they are not readily accessible when it is desired that the heater be serviced. This means that the servicing of the heater is complicated.

This invention provides a novel structure for releasably and yet firmly mounting the burner assembly to an adjacent lower end of the heat exchanger of an air heater of the type referred to above. The mechanism includes a pair of resiliently biased lugs which are readily accessible from the front of the heater when servicing is desired. This mounting mechanism is simple, effective, and economical.

Generally speaking, this invention resides in an air heater which includes a vertical heat exchanger having an open lower end, and burner assembly mounted adjacent the lower end of the heat exchanger. The heat exchanger has a downward extension to which the burner assembly is mounted. The invention comprises improved means for releasably mounting the burner assembly in position relative to the lower end of the heat exchanger. This mounting mechanism includes projection means extended rearwardly from the burner assembly. The extension defines means for receiving and supporting the projection means. The burner assembly defines an aperture at each end thereof. A pair of lugs, each configured to register with the apertures, are provided, together with resilient means for mounting each lug to the extension and for positioning the lugs for registry with the respective apertures when the burner assembly is in position adjacent the lower end of the heat exchanger with the projection means engaged with and supported by the receiving means. The lugs normally register in the apertures so that the burner assembly is supported in the extension. The lugs, however, are movable out of registry with the apertures against the bias of the resilient means so that the burner assembly is removable from the heat exchanger merely by disengagement of the projection means from their receiving means.

The above-mentioned and other features of the present invention are more fully set forth in the following detailed description of a preferred embodiment of the invention taken in conjunction with the accompanying drawings wherein:

FIG. 1 is a front elevation view of the lower end of an air heater equipped with the burner assembly mounting means of this invention;

2

FIG. 2 is a cross-sectional elevation view showing the burner assembly in position adjacent the open lower end of the air heater heat exchanger;

FIG. 3 is an enlarged cross-sectional plan view of a preferred mounting mechanism according to this invention; and

FIG. 4 is a cross-sectional elevation view taken along line 4—4 of FIG. 3.

FIGURE 1 shows an air heater 5 which includes a vertically extending rectangularly cross-sectional tubular heat exchanger 6 equipped with a downwardly extending skirt or extension 7. The skirt has vertically disposed surrounding sides 8 and a back 9 disposed below the corresponding surfaces of the heat exchanger around the open lower end of the heat exchanger. The heat exchanger itself is supported on a floor 13, or the like, by a pair of legs 14 secured to the sides of the heat exchanger and extending downwardly therefrom.

A burner assembly 15 is releasably mounted to the lower end of the heat exchanger adjacent the open end thereof via skirt 7. The burner assembly includes a burner element 16 (see FIG. 2) having an inlet throat 17 and a thermostatically operated pilot light unit 18. A gas supply duct 19 is connected to the throat of the burner element via an assembly 20 of burner assembly control devices which do not form a portion of this invention and, therefore, are not described in detail. It is sufficient to note, however, that assembly 20 includes both main gas and pilot light control valves and a main gas flow regulator. The burner assembly also includes a pan 22 defining a rectangular central opening 23 bounded on its forward and rear sides by depending flanges 24 and 25 extending downwardly from the pan. The burner element is secured to flanges 24 and 25 by screws 26. An air deflector 27 has a vertical leg 28 secured at its upper end to flange 25. The deflector also has a horizontal leg 29 which extends forwardly of the burner assembly around throat 17 of the burner element.

A U-shaped handle 30, having a portion 31 disposed parallel to flange 25, extends rearwardly from the upper end of leg 28 of shield 27. The lower extremity of skirt rear wall 9 defines a horizontally disposed, forwardly extending flange 32. When the burner assembly is in its operating position adjacent the lower end of the heat exchanger, as shown in FIG. 2, the lower edge of handle portion 31 is supported on the upper surface of flange 32. Accordingly, handle 30 defines a projection extending rearwardly from the burner assembly, and flange 32 defines means for receiving and supporting the projection to assist in maintaining the burner assembly in the desired position relative to the heat exchanger.

As illustrated in FIGS. 1 and 2, pan 22 at its opposite ends defines a pair of upstanding lugs 35 and 36. An aperture 37 is formed through each of these lugs. As illustrated in FIG. 1, when the burner assembly is in its proper operative position adjacent the lower end of the heat exchanger, apertures 37 register with slot apertures 38 formed in the sides of skirt 7 adjacent the vertically extending front edges thereof.

FIGS. 3 and 4 illustrate a preferred mechanism for releasably securing the burner assembly to the heat exchanger in cooperation with the coaction between handle 30 and skirt flange 32. A resilient metal strip 40 is disposed adjacent each of the opposing surfaces of skirt sides 8. Each strip is secured to the skirt at a location spaced rearwardly from the front vertical edge of the respective skirt side walls. Preferably the point of connection of each resilient strip is directly rearwardly of the respective slot apertures 38. Each strip extends forwardly along the inner surface of the skirt wall to beyond the front edge of the skirt. At this location, each strip 40 is bent toward the other strip for a short distance and

then forwardly to a cantilevered end 41. The configuration of each strip 40 adjacent its cantilevered end 41 defines a manually engageable tab 42 whereby the strip is movable away from the skirt against the bias of the strip. Preferably each strip is connected to skirt 7 by a pair of lips 43 formed integral with the strip and engaged in an aperture 44 formed in the skirt directly rearwardly of the respective slot aperture.

Each strip 40 mounts a lug or detent projection 45 adjacent the respective slot aperture 38. Each strip is biased so that the normal position of the associated detent projection is in registry with the adjacent slot aperture, i.e., so that the detent projection extends through the slot aperture. Preferably, each detent projection 45 is formed integral with the corresponding resilient strip 40.

As illustrated in FIGS. 3 and 4, when the burner assembly is in its operative position adjacent the lower end of heat exchanger 11, upstanding lugs 35, 36 of burner assembly pan 22 are disposed between strips 40 and skirt side walls 8 with lug apertures 37 registered with a slot apertures 38 and with lugs 45 passing through the registered apertures. Accordingly, the burner assembly is held securely and firmly in position relative to the heat exchanger. As noted above, further positioning and support of the burner assembly relative to the heat exchanger is provided by coaction between handle 30 and skirt flange 32.

When it is desired to remove the burner assembly from the air heater to service the burner assembly, a serviceman need only move tabs 42 toward each other to clear detent projections 45 from engagement within aligned apertures 37 and 38. Such disengagement of the detent projections from the registered apertures allows the burner assembly to be pivoted downwardly away from the heat exchanger; the fulcrum for such pivotal movement is at the connection between handle 30 and skirt flange 32. After burner element 16 clears the open lower end of the burner assembly, the serviceman then merely disengages handle 30 from skirt flange 32. After servicing of the burner assembly is completed, the process is reversed to restore the burner assembly to its operative position relative to the heat exchanger.

There has been described above novel, simple, effective, and efficient means for releasably, yet securely and firmly mounting the burner assembly of an air heater in operative position relative to a heat exchanger of the air heater. The burner assembly mounting structure is readily accessible from the front of the air heater and does not require the use of any tools for its operation.

It is to be understood that the structure described above constitutes a presently preferred embodiment of this invention and that modifications of this structure, within the scope of this invention, are within the talents of one having ordinary skill in the art to which the invention relates. Accordingly, the following claims, and the reasonable equivalents of the structures defined therein, rather than the foregoing description, define the true scope of this invention.

What is claimed is:

1. In an air heater including a vertical heat exchanger having an open lower end and a burner assembly mounted adjacent the lower end of the heat exchanger, the heat exchanger having a downward extension mounting the burner assembly, the improvement comprising means for releasably mounting the burner assembly in position relative to the lower end of the heat exchanger including projection means extended rearwardly of the burner assembly, the extension defining means for receiving the projection means, the burner assembly defining an aperture at each end thereof, a pair of lugs configured to register with said apertures, resilient means mounting each lug to the extension and positioning the lugs for registry with

the respective apertures when burner assembly is in position adjacent the lower end of the heat exchanger with the projection means engaged with the receiving means, the lugs normally being registered in the apertures to support the burner assembly in the extension but being movable out of registry with the apertures against the bias of the resilient means so that the burner assembly is removable from the heat exchanger.

2. In an air heater including a vertical duct-type heat exchanger having an open lower end and a burner assembly mounted adjacent the lower end of the heat exchanger, the improvement comprising means for releasably mounting the burner assembly in position adjacent the lower end of the heat exchanger including means at opposite ends of the burner assembly each defining an aperture, a downward extension of the exchanger rear and side walls within which the burner assembly is adapted to fit, the extension adjacent each of the exchanger side walls defining apertures arranged to register with the corresponding ones of the burner assembly apertures, projection means extended rearwardly of the burner assembly, receiving means below the exchanger rear wall adapted to cooperate with the projection means to support the burner assembly, and resiliently biased means carried by the extension proximate to each of the apertures therethrough, each resiliently biased means defining a projecting detent normally disposed in the extension aperture and extended therebeyond into engagement with the corresponding burner assembly aperture to support and position the burner assembly relative to the heat exchanger in cooperation with said projection means, the resiliently biased means being operable against the bias thereof to disengage the detents from the burner assembly apertures so that the burner assembly is removable from the exchanger.

3. In an air heater including a vertical duct-type heat exchanger having an open lower end and a burner assembly mounted adjacent the lower end of the heat exchanger, the improvement comprising means for releasably mounting the burner assembly in position adjacent the lower end of the heat exchanger including a downward extension of the exchanger rear and side walls, the extension below the exchanger rear wall defining a projection extending toward the front of the exchanger, a carrier pan adapted to fit horizontally within the extension and to which the components of the burner assembly are mounted, the carrier pan having a projection extending rearwardly therefrom, the carrier pan and the extension cooperating when the carrier pan is fitted into the extension with the carrier pan projection resting on and supported by the extension projection to define two pairs of aligned apertures therethrough adjacent the front of the heat exchanger, and resiliently biased means carried by the extension proximate to each of the apertures therethrough each resiliently biased means defining a projecting detent normally disposed in the extension aperture and extended therebeyond into engagement with the carrier pan apertures to support and position the burner assembly relative to the heat exchanger in cooperation with said projections, the resiliently biased means being operable against the bias thereof to disengage the detents from the carrier pan apertures so that the carrier pan and the apparatus carried thereby is removable from the extension.
